ABSTRACT OF THE DISCLOSURE

Apparatus for producing a wrapped tobacco rod comprises a first conveyor which is provided with a groove for advancing a tobacco stream and which comprises a foraminous member forming the bottom wall of the groove, a suction chamber for drawing a current of air across the tobacco stream in the groove and through the foraminous member to compress the tobacco stream against the foraminous member, a second conveyor which feeds tobacco into the groove to form the stream, a mechanical compressing device which compresses tobacco in the groove so that the tobacco stream undergoes mechanical and pneumatic compression, a trimming device for equalizing the mechanically and pneumatically compressed stream by removing surplus tobacco whereby the thus trimmed stream forms a filler rod, a third conveyor for receiving the filler rod from the first conveyor, and a wrapping device for applying a wrapper to the filler rod on the third conveyor.

This is a division of our copending application Ser. No. 862,386, filed Dec. 28, 1959, now patent No. 3,261,364, issued July 19, 1966.

The present invention relates to cigarette making machines in general, and more particularly to a method and apparatus for transforming loose tobacco into a continuous tobacco rod.

It is an object of the invention to provide a method and apparatus for producing a continuous tobacco rod having a high degree of uniformity in cross section and in weight. Such tobacco rods are utilized in the production of continuous cigarette rods by wrapping tobacco filler rods into strips or webs of cigarette paper, the cigarette rods so produced being then severed to form cigarettes of requisite length.

The method of the present invention comprises forming a continuous travelling stream of tobacco which may have and usually has an uneven cross section, supplying additional quantities of tobacco to the stream, and then removing excess tobacco from the stream at a point downstream of the point of admission of such additional quantities to form a tobacco rod of uniform cross section which is ready to be wrapped into cigarette paper.

In the production of a cigarette rod the levelled tobacco stream meets a strip of cigarette paper and the tobacco stream and the paper are then moved through a conventional rod-forming device which wraps the tobacco rod within the cigarette paper to form a continuous cigarette rod which is thereafter cut into cigarette lengths.

A tobacco rod of these properties and produced according to the present invention has a high degree of uniformity between any spaced portions containing additional tobacco and cigarettes cut from a cigarette rod produced from such a rod have a high degree of uniformity in weight.

2

The features of the present invention are shown by way of example on the accompanying drawings in which:

FIG. 1 is a side elevational view of an apparatus which comprises a suction wheel;

5 FIG. 2 is a fragmentary side elevational view of a second apparatus which constitutes a modification of the apparatus shown in FIG. 1;

FIG. 3 is an end elevational view as seen from the left-hand side of FIG. 2;

FIG. 4 is a diagram showing another mode of forming a tobacco rod of constant cross section;

FIG. 5 is a side elevational view of a third apparatus which may be used to produce a tobacco rod in a manner as shown in FIG. 4;

15 FIG. 6 is an enlarged fragmentary end elevational view of a dual suction wheel which is utilized in the apparatus of FIG. 5;

FIG. 7 is an enlarged fragmentary radial section through the dual suction wheel of FIG. 5;

20 FIG. 8 is a side elevational view of a modified trimming device which may be utilized in the apparatus of our invention;

FIG. 9 is an end elevational view of the trimming device shown in FIG. 8;

25 FIG. 10 is an enlarged fragmentary end elevational view of the dual suction wheel substantially as seen from the right-hand side of FIG. 5;

FIG. 11 is a fragmentary end elevational view of a modified dual wheel which cooperates with a modified trimming device, a portion of the wheel being shown in radial section;

30 FIG. 12 is a fragmentary end elevational view of another portion of the dual wheel shown in FIG. 11;

FIG. 13 is a side elevational view of an apparatus which 35 embodies the dual wheel of FIGS. 11 and 12, certain parts of the apparatus being broken away and certain other parts being shown in vertical section;

FIG. 14 is a side elevational view of a suction conveyor which may be utilized to transfer a tobacco rod 40 from the suction wheel to a rod forming mechanism; and

FIG. 15 is an enlarged fragmentary axial section through the drive for the dual wheel of the apparatus shown in FIG. 13.

Various constructional forms of apparatus embodying 45 the features of this invention will be explained with reference to the constructions shown in the accompanying drawings in which in every case a distributor 15 is adjusted to supply precisely the quantity of tobacco required to form the rod used for making the cigarettes.

FIG. 1 shows an under-feed machine where the tobacco is showered from a distributor 15 upon an endless belt 1f guided over support rollers 17f, 18f of which the roller 18f is positioned adjacent a rotary wheel 19f having a grooved periphery so that the belt 1f meets the lower peripheral part of the wheel 19f. A stream of tobacco 2f formed on the belt 1f by the action of the distributor 15 is transferred into the groove of the wheel 19f and moves through approximately one half of the perimeter of the wheel 19f, subsequently leaving the groove at a higher level. The stream of tobacco formed on the belt 1f and transferred to the groove of the wheel 19f may exhibit certain irregularities and the high portions are trimmed off by means of a cutting or trimming device 7f which consists of a rotating cutter disc. The tobacco rod 21f leaving the upper portion of the wheel 19f is of uniform cross-section and weight. This rod leaves the wheel 19f over a bridge 22 and then meets a cigarette paper strip 23 which is supported by a forming belt 24 which causes the paper strip 23 and the tobacco rod 21f thereon to move through a conventional cigarette rod-forming device 25, which results in the enclosure of the tobacco rod

21f in the paper strip **23** to form a continuous cigarette rod **26** which thereafter is cut into cigarette lengths. The tobacco removed by the trimming device **7f** is collected by a pneumatic conveyor device **27f** having a collecting funnel **28** to receive the tobacco which is then delivered through a delivery member **29f** into the downwardly moving portion of the groove of the wheel **19f**, namely at a point in advance of the point where the stream **2f** enters the groove.

FIGS. 2 and 3 illustrate an arrangement generally similar to that shown in FIG. 1 but in place of using the pneumatic conveyor means **27f** for receiving the tobacco removed by the action of the cutting or trimming device **7f** an endless conveyor device **29** is used. This conveyor device may comprise an endless carding belt and it may be positioned somewhat obliquely as indicated in FIG. 3, to tobacco being removed from the carding belt by means of a spiked wheel **30** or the like and distributed upon the surface of the tobacco stream **2g** carried by the endless conveyor belt **1g**. In this case the tobacco is received from the trimming device **7g** by means of an obliquely positioned guide chute **31** which delivers the removed tobacco on to the carding belt.

In FIGS. 1 and 2 a rotary wheel **19f** is employed to raise the tobacco stream to a higher level and the tobacco stream is subjected to a trimming operation while moving upwardly and along the periphery of the wheel. It is desirable to provide suction means within the confines of the rotary wheel for holding the tobacco stream in the groove. For this purpose the wheel is rotatable with respect to a stationary internal suction chamber defined by radial walls **32** and **33** so that a portion of the periphery between the walls **32** and **33** where the tobacco stream is in contact with the wheel is retained by suction. Removal of the tobacco rod from the periphery of the wheel is assisted by means of compressed air delivered through the uppermost portion of the periphery of the wheel between the radial walls **34** and **34a** of a compressed air duct which constitutes a stripping means for the tobacco rod.

If desired the suction means can be rendered inoperative along that section of the groove which is adjacent the trimming device **7**. This can be achieved by providing the suction chamber with additional radial walls **35** and **35a** between the radial walls **32** and **33**. Outward movement of the tobacco stream between the walls **35** and **35a** is prevented if the trimming device **7g** is constructed as indicated in FIG. 3 or 11. This trimming device comprises a pair of interengaging star wheels **36** and a rotary cutter disc **37** which overlies the star wheels.

In another mode of carrying out the invention which is illustrated diagrammatically in FIG. 4 and in a practical form in FIG. 5, the rotary wheel **19i** is provided with two parallel disposed circumferential grooves **191**, **192** (see FIG. 6), the former is used for receiving the tobacco stream **2i** in the same way as shown in FIGS. 1 and 2 while the second groove **192** provides the return path for the tobacco removed from the surface of the tobacco stream travelling in the first groove by the action of a trimming or levelling device which in this case is shown as consisting of an obliquely positioned brush **38**. It will be noted with reference to FIG. 4 that the incoming stream **2i** of tobacco containing the quantity of tobacco required to form the desired rod section is fed to the feed wheel **19i** and the surface portions of said stream comprising the irregularities thereof are formed into a branch stream **39** which travels along the part of the periphery between the outgoing rod **21i** and the incoming tobacco stream **2i**. This branch stream of tobacco **39** is spread onto and mingles with the upper surface of the tobacco stream **2i** moving towards the wheel **19i** and comes to lie between the stream and the wheel, that is on the opposite surface of the stream to that which has the irregularities, which latter are subjected to the levelling or trimming action at the point **40**.

Referring now to the construction of the machine shown in FIGS. 5 to 7, it will be noted that a shower of tobacco is delivered by the distributor **15** upon the surface of an endless travelling belt **1i** which feeds the stream of tobacco **2i** toward the first groove **191** of the wheel **19i**, the conveyor belt **1i** being guided in an endless path over suitable supporting rollers **17i**, **18i** and **20i** positioned so as to cause the belt **1i** to engage a small peripheral portion of the wheel **19i** and to ensure the transfer of the stream **2i** into the groove of the wheel **19i** where it is retained by suction in a manner already explained with reference to FIGS. 1 and 2. A suction chamber defined by the space between the radial walls **33i** and **32i** in the zone of the wheel receiving the tobacco stream **2i** serves to hold said tobacco stream in the first groove **191** of the rotary wheel **19i** (see also FIG. 6). Conveniently and as shown, the suction action terminates shortly before the rotary cylindrical brush **38**, serving as the levelling or trimming device, is operative so that the tobacco is permitted to expand substantially to its uncompressed condition before it is subjected to the levelling operation by the brush **38**. Alternatively the chamber defined by the radial walls **33i** and **42** may extend up to the point where the tobacco rod leaves the top part of the wheel **19i**. Likewise a compressed air delivery chamber similar to **34** in FIG. 1 may be utilized to assist in the discharge of tobacco stream from the wheel.

If desired and as shown in FIG. 5, a perforated endless belt **44** may be positioned above the take-off point for the tobacco rod **21i** and a suction box **45** positioned within the space encircled by the belt **44** above the lower stretch **44a** may be used to exert an upwardly directed holding action upon the tobacco rod **21i** to assist its removal from the peripheral groove **191** in the wheel **19i**.

As best shown in FIG. 6 the second groove **192** in the rotary wheel **19i** receives the tobacco swept from the tobacco stream carried in the first groove **191** and carries the trimmed portion of tobacco into the path indicated by **39** in FIG. 4. The bristles of the brush **38** induce a current of air, and said brush is so positioned that the induced current causes the removed tobacco to move in the direction towards the second groove **192**. Suction is operative in this groove over that portion of the circumference thereof arranged between the brush **38** and the radial wall **43** in FIG. 5 so that the tobacco received in the groove **192** by the action of the rotary brush **38** is retained in said groove and is subsequently collected by a suitably positioned deflector member **46** and transferred into the first groove **191** as shown in FIG. 10, the transferred tobacco being then held by suction in the first groove **191** at a point shortly before the point where the tobacco stream **2i** is pressed into the groove **191** by the action of the endless conveyor belt **1i**.

The tobacco rod **21i** removed from the groove **191** by the action of suction on the lower horizontal stretch **44a** of the perforated belt **44** and the suction box **45** is placed upon a paper strip **23** suitably guided into the cigarette rod making machine and also supported by the usual tobacco rod forming endless belt **24** which moves the paper strip **23** and the tobacco rod **21i** through a cigarette rod forming device **25**, the finished cigarette rod being shown at **26**.

FIG. 7 shows in section a portion of the rotary wheel **19i**. It will be noted that the first groove **191** includes a bottom surface formed by a perforated annular metallic wall **48**. The section shown in FIG. 7 corresponds to the position where the rotary brush **38** is located, and it will be observed that any high portions of the tobacco stream located in the groove **191** are swept in the direction indicated by the arcuate arrow **49** into the second groove **192**. The latter is defined on one side by an annulus **51** of perforated metal enclosed by a casing member **52** providing a suction box which maintains a suction over that part of the side wall of the groove **192** where the tobacco is to be conveyed from the receiving point formed

by the rotary brush 38 to the delivery point formed by the tobacco deflector 46.

FIGS. 8 and 9 show an alternative to the rotary brush 38 formed in this case by an endless belt 53 positioned obliquely relatively to the circumference of the wheel 19i and serving to transfer tobacco from the first groove 191 into the second groove 192 by the action of the induced current of air. It will be understood that in all embodiments of our invention wherein a rotary brush 38 or an endless belt 53 is employed, such combined trimming and transferring devices not only induce a current of air but they also serve as a means for mechanically moving tobacco particles into the path in which the tobacco particles return toward the tobacco stream. The combined trimming and transferring device 38 or 53 is particularly useful in such tobacco processing machines in which the trimming or levelling operation is carried out while the tobacco stream is held in the groove 191 by suction. If the tobacco stream is not held by suction during the trimming or levelling operation it is often advisable to employ trimming means of the type shown in FIG. 3. The star wheels 36 hold the particles of tobacco during trimming so that the trimming operation does not affect the distribution of tobacco particles in the groove of the wheel.

FIGS. 11 to 13 and 15 show further modifications applicable to a construction of the character shown in FIGS. 4 to 10 employing a rotary wheel 19k having adjacently positioned grooves 191k, 192k. In the FIGS. 11 to 13 and 15 the tobacco transferred into the second groove 192k as a result of the action of the trimming or levelling device is retained in said groove by mechanical means, in particular by the arrangement of a spiked or carded surface in said groove. Furthermore, the second groove 192k forms an independent wheel unit which is caused to rotate at a substantially slower speed than the other part of the wheel provided with the first groove 191k.

As shown in FIG. 13, a construction is employed which is similar to that shown in FIG. 5 in that the tobacco is showered by a distributor 15 upon the surface of an endless belt 1i supported by guide rollers 17i, 18i and 20i positioned so that the tobacco stream 2i formed on the surface of the belt 1i is pressed into the first groove 191k where it is held by suction by the action of a suction chamber formed between the radial walls 33k and 35k. In this embodiment the trimming step is performed by means of a rotary cutter disc 37 (FIG. 11) cooperating with a pair of interengaging star wheels 36 as already explained in connection with FIG. 3, the suction being rendered ineffective along the trimming station in the zone between the radial walls 35k and 35k', which zone divides the suction chamber into two sections lying respectively between the radial walls 33k and 35k and between the radial walls 32k and 35k'. Removal of the tobacco rod 21 is facilitated by the provision of a compressed air channel formed between the radial walls 34k and 34k'. The tobacco rod as shown in FIG. 14 may alternatively be removed from the groove 191k by a perforated belt 44 and a suction nbox 45 as also explained in connection with FIG. 5, or as shown in FIG. 13 a bridge or doctor member 55 can be provided. As in the previous embodiments the outgoing tobacco rod 21 meets a paper strip 23 and the latter and the rod are supported by an endless forming belt 24 which conveys these components through a rod-forming device 25 to form the finished cigarette rod 26.

As already stated the groove 192k is arranged in a separate wheel 193 which is caused to rotate at a slower speed than the wheel 19k and is provided with points or bars in the manner of a carding belt on its base surface to receive tobacco removed by the action of the elements 36, 37 as a result of the trimming or levelling of the tobacco stream in the channel 191k. This removed to-

bacco is deflected into the groove 192k by means of a suitable guide member 58 and is carried around said groove 192k up to the point where it is stripped from the groove by the action of a picker roll or rotary brush 59. A suitably positioned deflector 61 shown in FIG. 12 serves to divert the tobacco removed from the groove 192k by the member 59 onto the surface of the tobacco stream 2i before it moves into the groove 191k.

FIG. 15 shows the construction and drive of the wheel 19k and its associated parts. The main part of the wheel 19k including the peripheral groove 191k therein, the bottom of which is formed by a perforated screen 48k and through which suction is transmitted, is provided with radial passages 62 leading to a stationary suction box 63 by means of a connecting passage 62k so that suction will be exerted in desired peripheral zones between the radial walls 32k and 35k' and also between the radial walls 35k and 33k as shown in FIG. 13. The outer part 193 of the wheel which is provided with the groove 192k comprises a barbed bottom wall and is supported on a shaft 70 rotatable within a sleeve 63k carrying the wheel 19k proper. The sleeve 63k carries fixedly thereon a gear wheel 64 meshing with a gear 65 integrally formed with a gear wheel 67 meshing with a driver gear 68 fixedly mounted on the shaft 70, the twin gear wheels 65, 67 being mounted on a stub shaft 69 fixed to the frame of the machine. The gear 68 is driven by a suitable motor or another source of power and drives the shaft 70 which in turn drives the wheel 193 at a first speed. The gears 67, 65 which are driven by the gear 68 transmit motion to the gear 64 which drives the wheel 19k at a second speed higher than the speed of the wheel 193.

The apparatus shown in FIGS. 13 and 15 operates as follows: The tobacco delivered by the distributor 15 at an average rate corresponding to the desired cigarette rod 26 forms a tobacco stream on the endless belt 1i. This tobacco stream is pressed into the groove 191k of the wheel 19k and is retained therein by suction. As the tobacco stream carried in the groove 191k passes the trimming or levelling device 36, 37, the suction holding action is preferably discontinued and the tobacco trimmed off the surface of the tobacco stream in the groove 191k is transferred into the second groove 192k, the remainder of the tobacco stream which is of uniform cross-section and of constant density then forming the tobacco rod 21 which is wrapped into the paper strip 23 to form the cigarette rod 26.

The tobacco removed by the trimming device 36, 37 is transferred into the second and slower moving groove 192k of the wheel 193 and is removed therefrom by the action of the picker member 59 (FIG. 13), and is then spread over the surface of the tobacco stream 2i just before it is pressed into the groove 191k.

In all the embodiments described means may be provided for measuring the amount of removed tobacco, such as the tobacco in the groove 192k of the rotary wheel in FIGS. 11 to 13 and 15, or the tobacco in the stream 2f on the conveyor belt 1f in FIG. 1, or the tobacco in the stream on the endless belt 29 in FIG. 2.

Furthermore, additional means may be provided for measuring the finished tobacco rod or cigarette rod and for controlling the action of the trimming or levelling devices 7f, 7g, 38, 53, for instance, by advancing or retracting these devices more or less from the surface of the tobacco stream or rod. The measuring means may be the same as or similar to that disclosed in the copending application of Willy Richter, Ser. No. 110,561, filed May 16, 1961.

Without further analysis, the foregoing will so fully reveal the gist of the present invention that others can, by applying current knowledge, readily adapt it for various applications without omitting features which fairly constitute essential characteristics of the generic and specific aspects of our contribution to the art and, therefore, such adaptations should and are intended to be compre-

hended within the meaning and range of equivalence of the following claims.

What is claimed as new and desired to be protected by Letters Patent is:

1. In an apparatus for producing a wrapped tobacco rod, first conveyor means having an elongated groove for advancing a stream of tobacco and comprising a foraminous member forming the bottom wall of said groove, said conveyor means further comprising a suction chamber adjacent to said foraminous member opposite said groove for drawing a current of air across the tobacco stream and for thereby compressing the tobacco stream against said foraminous member; second conveyor means for feeding tobacco in excess of that required to produce said rod into said groove whereby the tobacco thus fed forms said stream; mechanical compressing means for compressing the tobacco stream in said groove so that the action of said mechanical compressing means is superimposed upon the compressing action of said air current; trimming means for equalizing the tobacco stream by removing surplus tobacco to thus convert the tobacco stream into a filler rod, said trimming means being located downstream of said mechanical compressing means; third conveyor means for receiving the filler rod from said first conveyor means; and wrapping means for wrapping the filler rod on said third conveyor means.

2. A method of manipulating tobacco in the production of wrapped tobacco rods, comprising the steps of conveying a stream containing tobacco particles in excess

5
10

of that required to produce a rod lengthwise along an elongated path; subjecting the travelling tobacco stream to mechanical and pneumatic compressing actions to form a condensed tobacco stream; terminating the application of the mechanical compressing action and thereupon trimming the tobacco stream to remove surplus tobacco so that the thus trimmed stream forms a tobacco filler rod; pneumatically collecting the surplus of tobacco; and applying a wrapper around the filler rod to form a wrapped tobacco rod.
